SPUTUM CUP

Harold B. Cranshaw, Newton, Mass., assignor to
Burnitol Manufacturing Company, Charles-
town, Mass., a corporation of Maine

Application October 8, 1942, Serial No. 461,272

14 Claims. (Cl. 4—271)

This invention relates to receptacles of the type made from sheet material, such for example as sputum cups and like containers which are intended to be destroyed after use.

In articles of this character it is essential that the receptacle be provided with a suitable cover which is normally closed and which may be conveniently opened, and it is the principal object of the present invention to provide a receptacle of this type having a normally closed cover member which is hinged to the receptacle without the use of fastening means other than those constituting an integral part of the cover and receptacle and which is constructed so that the cover may be conveniently opened by the hand or finger holding the receptacle.

Another object is to provide a receptacle wherein the cover may be integral with or separate from the cup, but in either case both parts being formed with complementary interlocking means so designed that the receptacle may be quickly erected and assembled so that the parts are not subject to accidental separation.

Further objects will be apparent from the following description and the accompanying drawings wherein

Fig. 1 is a plan view of a blank from which a cup embodying the present invention is formed;

Fig. 2 is a plan view of the cup;

Fig. 3 is an enlarged fragmentary perspective showing the manner in which the cover is assembled with the cup;

Figs. 4, 5 and 6 are views corresponding to Figs. 1 to 3 but showing a further modification;

Fig. 7 is a fragmentary plan view of a blank from which a cup having an integral cover is formed; and

Fig. 8 is an enlarged fragmentary perspective of the parts in erected position.

Each of the embodiments herein shown comprises a cup C formed from a single piece of fiberboard or the like sheet material, and a cover which may be separate from or integral with the cup, in either case the cup and cover being formed with complementary interlocking parts which not only pivotally support the cover in normally closed position on the cup but also prevent separation of the parts.

In the embodiment shown in Figs. 1 to 3 the cup is formed from a blank B scored to provide lines of fold (indicated by the dot and dash lines of Fig. 1) which define a bottom 1, side walls 2, 3, 4 and 5 interconnected by foldable portions 6, 7, 8 and 9. The outer edges of side walls 2 and 4 are provided with integral locking flaps 10 and

11 having wings which are adapted to interlock with the foldable portions 6—9 to hold the cup in erected position.

The side wall 3 is formed with an extension 12 which is scored to provide a line of fold defining a hinged cover-supporting section 14 and a locking tongue 15, the inner edges 16 and 17 of the section 14 being tapered, as shown in Fig. 1. The cover 20 (Fig. 2) is provided adjacent to its rear edge with a pair of spaced slits 21 and 22 which define a resilient depressible locking strap 24. When the cup is erected, the extension 12 is inserted through the slits 21, 22 so that the tapered edges of the section 14 are wedged against the ends of the slits with its body portion holding the resilient strap 24 in depressed position, as shown in Fig. 3. The strap 24 is thus effective to exert a frictional locking action on the section 14 and cooperates with the wedging action on the tapered edges 16 and 17 so as pivotally to hold the cover 20 in normally closed position on the cup. The locking tongue 15 is bent about the rear edge of the cover with its end inserted through slit 21 so as to underlie the body portion of the cover, thereby forming an interlock which prevents the cover from being separated from the cup.

In the embodiment shown in Figs. 4 to 6 the cup is formed from a blank which is substantially identical to that of the previously described embodiment, except that the wall 3 is formed with an extension 25 scored to provide lines of fold defining a pair of cover supporting sections 26, 27 and lateral locking tongues 28. The sections 26, 27 when folded together provide a dovetail-shaped hinged support for cover 30 which is also formed with a dovetail-shaped rear end portion 31 and these sections are slit as indicated at 32 and 33 so as to provide depressible areas 34 and 35. When the cup is in erected position and assembled with the cover, the sections 26, 27 extend about the rear portion 31 with the slits 32 and 33 registering, and the locking tabs 28 may be folded inwardly. By depressing the areas 34, 35 the ends of the tabs 28 may be inserted through the slits and held beneath the rear of the cover 30, as shown in Fig. 6, thereby providing an interlock which not only supports the cover in normally closed position, but also prevents separation of the parts.

The embodiment shown in Figs. 7 and 8 is similar to that of Figs. 4 to 6, except that the cover 40 is formed integrally with supporting section 41 carried by side wall 3. The section 41 is formed with lateral locking tongues 42 and

both the cover and supporting section are provided with slits 43 which define depressible areas 45. When the cup is erected the cover 40 may be folded downwardly on the cup to provide a closure and the locking tongues folded inwardly with their ends inserted through slits 43, as shown in Fig. 8, to provide an interlock which prevents separation of the parts.

It will be noted that in each of the embodiments herein shown the cover is securely held in assembled relation with the cup by means of one or more tongues formed integral with the cover-supporting section, which tongues cooperate with slotted portions of the cover to form an interlock preventing separation of the parts. It will also be noted that the marginal portion of the cover overlying the supporting tongue or section provides a lever-like handle by means of which the cover may be conveniently swung open when the cup is held in the hand.

While I have shown and described different desirable embodiments of the invention, it is to be understood that this disclosure is for the purpose of illustration and that various changes in shape, proportion, and arrangement of parts, as well as substitution of equivalent elements for those herein described, may be made without departing from the spirit and scope of the invention as set forth in the appended claims.

I claim:

1. A receptacle of the class described comprising a cup having a side wall formed with an extension bent outwardly to form a hinge, said extension having a bendable portion constituting a locking tongue, and a cover having a slit in its rear marginal portion defining an area adapted to be depressed from the plane of the cover, said extension underlying the cover with its locking tongue bent about the adjacent edge of the cover and inserted through said slit to form an interlock which pivotally supports the cover in normally closed position and prevents separation of the parts.

2. A receptacle of the class described comprising a cup having a side wall formed with an extension bent outwardly to provide a hinge, said extension having laterally extending locking tongues, and a cover having in its rear marginal portion slits defining depressible areas, said extension underlying the rear marginal portion of the cover with its locking tongues folded about said depressible areas and its ends inserted through said slits, thereby to form an interlock which pivotally supports the cover in normally closed position and prevents separation of the parts.

3. A receptacle of the class described comprising a cup having a side wall formed with an extension defining a hinge and a locking tongue, and a cover having at its rear edge portion slits defining a depressible area, said tongue being bent about the adjacent edge of the cover with its end inserted between the depressible area and the adjacent body portion of the cover, thereby to form an interlock which pivotally supports the cover in a normally closed position and prevents separation of the parts.

4. A receptacle of the class described comprising a cup having a side wall formed with an extension defining a hinge and a locking tongue, and a cover having adjacent to its rear edge a pair of spaced slits defining a resilient depressible strap, said tongue projecting through said slits and holding said strap in depressed position, the end of said tongue being bent about the rear

edge of the cover and inserted through the innermost slit, thereby to form an interlock which pivotally supports the cover in normally closed position and prevents separation of the parts.

5. A receptacle of the class described comprising a cup having a side wall formed with an extension bent outwardly to provide a hinge, said extension having laterally projecting locking tongues, and a cover having at its rear marginal portion and spaced inwardly from its lateral edges slits providing depressible areas at its rear corners, said extension underlying the rear marginal portion of said cover with its locking tongues folded inwardly over said depressible areas, the ends of said tongues extending through said slits to underlie the cover and thereby provide an interlock which pivotally supports the cover in normally closed position and prevents separation of the parts.

20 6. A receptacle of the class described comprising a cup having a side wall formed with an extension bent outwardly to provide a hinge, said extension having laterally projecting locking tongues, and a cover having a rear edge which 25 projects outwardly beyond the adjacent edge of the cup, the inner part of said extension underlying the rear edge of the cover with its outer part, folded over the upper face thereof, said extension and rear edge having slits defining depressible areas, the locking tongues being folded inwardly about said depressible areas with their ends projecting through said slits to form an interlock which pivotally supports the cover in normally closed position and prevents separation 35 of the parts.

7. A receptacle of the class described comprising a cup having a side wall formed with an integral extension including inner and outer sections, the inner section providing a supporting hinge and the outer section being bent upon the inner section to provide a cover for the cup, said sections having at each lateral edge inter-engaging integral parts constructed and arranged to provide an interlock effective to hold the cover in normally closed position and prevent separation of the parts.

8. A receptacle of the class described comprising a cup having a side wall formed with an integral extension including inner and outer sections, the inner section providing a supporting hinge and the outer section being bent upon the inner section to provide a cover for the cup, one of said sections being formed with a locking tongue at each lateral edge and the other section having cuts providing openings to receive said locking tongues, thereby to provide an interlock effective to hold the cover in normally closed position and prevent separation of the parts.

60 9. A receptacle of the class described comprising a cup having a side wall formed with an integral extension including inner and outer sections, the inner section providing a supporting hinge and the outer section being bent upon the inner section to provide a cover for the cup, the inner section having locking tongues at its lateral edges and the outer section having cuts defining openings to receive said locking tongues thereby to provide an interlock effective to hold the cover in normally closed position and prevent separation of the parts.

70 10. A receptacle of the class described comprising a cup having a side wall formed with an integral extension including inner and outer sections, the inner section providing a support-

ing hinge and the outer section being bent upon the inner section to provide a cover for the cup, the inner section having lateral locking tongues and the outer section having cuts at its side marginal portions defining openings to receive said locking tongues, thereby to provide an interlock effective to hold the cover in normally closed position and prevent separation of the parts.

11. A receptacle of the class described comprising a cup having a side wall formed with an integral extension including an inner section providing a supporting hinge and an outer section bent upon the inner section to provide a cover for the cup, the outer section having slits adjacent to its lateral edges providing openings and the inner section having laterally projecting locking tongues bent inwardly about the adjacent edges of the outer sections and inserted in said openings to provide an interlock effective to hold the cover in normally closed position and prevent separation of the parts.

12. A receptacle of the class described comprising a cup having a side wall formed with an integral extension including an inner section providing a supporting hinge and an outer section bent upon the inner section to provide a cover for the cup, the inner section having locking tongues at its lateral edges and the outer section having parts shaped to accommodate the ends of said tongues, thereby to provide an interlock effective to hold the cover in normally

closed position and prevent separation of the parts.

13. A receptacle of the class described comprising a cup having a side wall formed with an extension including inner and outer sections, the inner section swinging relatively to said side wall on a hinge line and the outer section being folded upon the inner section to extend parallel thereto, one of said sections having slits at its rear marginal portion and spaced inwardly from its lateral edges, each of said slits extending in a direction crosswise of said hinge line, and the other of said sections having locking tongues extending through said slits, each of said tongues extending in a direction lengthwise of said hinge line, to interlock the two sections together.

14. A receptacle of the class described comprising a cup having a side wall formed with an extension including inner and outer sections, the inner section swinging relatively to said side wall on a hinge line and the outer section being folded upon the inner section to extend parallel thereto, the outer section having slits at its rear marginal portion and spaced inwardly from its lateral edges, each of said slits extending in a direction crosswise of said hinge line, and the inner section having locking tongues extending through said slits, each of said tongues extending in a direction lengthwise of said hinge line, to interlock the two sections together.

HAROLD B. CRANSHAW.
